For Lemuel W. Perrell
UNITED STATES PATENT OFFICE.

DAVID PERRET, OF NEUCHATEL, SWITZERLAND:

WATCH.

SPECIFICATION forming part of Letters Patent No. 293,779, dated February 19, 1884,

Application filed November 14, 1883. (No model.) Patented in France May 1, 1883, No. 155,301.

To all whom it may concern:

Be it known that I, DAVID PERRET, engineer, a citizen of the Republic of Switzerland, residing at Neuchatel, in Switzerland, have invented an Improvement in Watches, of which the following is a specification.

The object of my invention is to reduce the number of parts in the mechanism for setting the hands of watches, so as to provide a device that shall be very simple in construction and not liable to get out of order.

The parts composing my device for setting the hands of watches consist of a wheel upon the central or minute-hand arbor, a wheel within a recess in the cap-plate, and meshing with the first-named wheel, and a key that is made with a square end, and a cylindrical portion between the squared end and a knob or button-head outside of the cap-plate. When the key is drawn outwardly, its squared end passes into the square opening in the center of the wheel, and by turning the key by means of the head motion is communicated through the gearing to the arbor of the center-wheel, and the hands are turned for setting them. When the key is pushed in, the cylindrical portion of the key comes within the square of the wheel; hence the turning of the key does not rotate said wheel, and no movement is given to the hands.

In the drawings, Figure 1 is a view of a watch with the back cover opened, showing the cap-plate with my improvement applied thereto. Fig. 2 is a section at the line *x y*. Fig. 3 is a section showing the key in the position it occupies when not in use, and Fig. 4 is a section with the key in position for setting the hands.

P is a cap-plate, that replaces the usual hinged inner case of a watch. This plate P is held in place by screws 2 2, that pass into the ring of the watch-case; but said plate may be secured in any desired manner. In consequence of this plate P not being hinged, I provide an opening in the plate P, in order that the balance O may be visible, and this opening is covered by a glass, v, held in place by a ring, L, that is screwed or otherwise fastened to the plate. I also provide a second opening at F S in said plate, to give opportu-

nity for moving the regulator T. This plate P might be made wholly of glass.

R is a wheel secured to the arbor of the center-wheel of the watch, and r is a wheel that occupies a recess in the plate P, or the space between the plates P and b, and gears with the wheel R. The wheel r has no arbor, but it has a square hole at its center, of a size to receive the square q upon the stem of the key Q. There is a plate or bridge-piece, b, next the plate P, to hold the wheel r in place, and there is a hole in this plate b of a size to allow the squared portion q of the key to turn freely therein. The key Q has a cylindrical portion between the squared portion and the knob or head, and when the key is in the position shown in Fig. 3 the squared portion q is out of the square hole in the wheel r, and the cylindrical portion of the key is within the square of said wheel r; hence any turning movement given to the key does not rotate the wheel r, and the wheel r is free to revolve around the cylindrical part of the key. When the key is drawn outwardly to the position shown in Fig. 4, the squared portion q fills the square hole in the wheel r, and by turning the key by means of the head or knob the wheel r is turned, and by its motion is given to the center-arbor of the watch and the hands are turned for setting them. The squared portion of the key prevents the key being pulled out too far and detached from the plate P; and if the key should not be pushed in after setting the hands it will be pushed in by the case E when that is closed.

It will be evident that the key Q, with its square, might be used to wind the watch, the key passing into the arbor of the spring-barrel, or the wheel r being geared to a wheel upon the arbor of the spring-barrel.

I claim as my invention—

1. The wheels R r and plate P, the wheel r having a square opening at its center, and the plate P having an opening for the stem of the setting-key, in combination with the setting-key having a squared portion, q, a cylindrical portion next to said squared portion, and a knob or button outside the plate P, substantially as and for the purposes specified.

2. The combination of the plate P, having 100

two openings, one at F S, to give access to the regulator, and the other over the balance O, in order that said balance may be visible, a glass, v, covering the last-mentioned opening, the key Q, and wheels R r, substantially as and for the purposes specified.

3. The combination, with the winding or setting portion in a watch, of a key, Q, hav-

ing the squared or prismatic end, the head, and the cylindrical portion between the square to end and the head, substantially as and for the purposes set forth.

DAVID PERRET.
